UNITED STATES PATENT OFFICE

125,048

DESIGN FOR A SKATE

Harvey J. de Blanc, Denver, Colo.

Application November 14, 1940, Serial No. 96,579

Term of patent 3½ years

To all whom it may concern:

Be it known that I, Harvey J. de Blanc, a citizen of the United States, residing at Denver, in the county of Denver and State of Colorado, have invented a new, original, and ornamental Design for a Skate, of which the following is a specification, reference being had to the accompanying drawing, forming part thereof.

In the drawing:

Fig. 1 is a side view of a skate showing my new design.

Fig. 2 is a front view thereof.

I claim:

The ornamental design for a skate, as shown.

HARVEY J. DE BLANC.
